UNITED STATES PATENT OFFICE

103,297

DESIGN FOR A SPECTACLE FRAME OR SIMILAR ARTICLE

Kathryn S. Barrett, Minneapolis, Minn.

Application September 26, 1936, Serial No. 65,019

Term of patent 14 years

To all whom it may concern:

Be it known that I, Kathryn S. Barrett, a citizen of the United States, residing at Minneapolis, in the county of Hennepin and State of Minnesota, have invented a new, original, and ornamental Design for a Spectacle Frame or Similar Article, of which the following is a specification, reference being had to the accompanying drawing, forming part thereof.

The figure is a perspective view of my spectacle frame or similar article showing my new design.

I claim:

The ornamental design for a spectacle frame or similar article as shown.

KATHRYN S. BARRETT.
